(57) **CLAIM**

The ornamental design for a tire, as shown and described.

DESCRIPTION

FIG. 1 is a perspective view of a tire showing my new design; FIG. 2 is a front view thereof, the rear, top plan, and bottom plan views being the same; FIG. 3 is a right side view thereof, the left side view being the same,

FIG. 4 is an enlarged view of the portion 4-4 in FIG. 2; and, FIG. 5 is a cross-sectional view taken along line 5'-5' in FIG. 4 to line 5-5 in FIG. 3.

In the drawings, the broken lines showing portions of the tire tread, sidewall, and inner bead depict portions of the tire which form no part of the claimed design.
